Primary Examiner — Cathron Brooks*Assistant Examiner* — Ian Whitmore(74) Attorney, Agent, or Firm — Yee & Associates, P.C.(57) CLAIM

The ornamental design for a display screen with graphical user interface, as shown and described.

DESCRIPTION

FIG. 1 is a front view of a first embodiment of a display screen with graphical user interface;

FIG. 2 is a front view of a second embodiment thereof;

FIG. 3 is a front view of a third embodiment thereof; and,

FIG. 4 is a front view of a fourth embodiment thereof.

The vertical dashed lines shown in solid outline beneath the top two circular dollar images are part of the claimed design. The outermost broken line perimeter illustrates a display screen and forms no part of the claimed design. The remaining broken lines illustrate portions of a graphical user interface and form no part of the claimed design.
